UNITED STATES PATENT OFFICE.

BERNARD STEINMETZ, OF PARIS, FRANCE, ASSIGNOR TO RAPHAEL NEUMANN & CO., OF NEW YORK CITY.

DESIGN FOR LOCK-CASES FOR SATCHELS, &c.

Specification forming part of Design No. 5,373, dated November 21, 1871.

To all whom it may concern:

Be it known that I, BERNARD STEINMETZ, of Paris, France, have invented a new Design for Lock-Case for Satchels, Valises, Bags, &c., of which the following is a specification:

The nature of my invention is fully represented in the accompanying drawing, to which reference is made, and where—

Figure I shows a top view, and Fig. II a front elevation.

A represents the bottom flanch, by which the lock-case is fastened to the bag, &c. B represents a raised oblong casing, containing the mechanism of the lock, similar to the raised and armored part of a ship-of-war, generally called monitor; and C represents a circular tower in the center of the oblong casing B. The oblong casing B is engraved on each side with figures a, representing port-holes, open, showing the ends of the guns, and likewise with suitable lines representing the edges of the plates used for armoring the monitors. The upper part of the

circular tower C is engraved so as to represent a light frame-work, similar to that usually erected on the top of monitor towers. On one side of this circular tower C the forward end of a gun, n, and on the opposite side the after end m of a gun, are attached.

Instead of engraving the desired designs upon the oblong and circular casing forming the lock-case, the same may be encased, stamped, embossed, or pressed into the same.

The distinctive character of my design is found in the representation of a miniature monitor for a lock-case, and from this style I propose to call the same the "Monitor lock."

What I claim as my invention is—

The design for a lock-case, representing a monitor, substantially in the manner above described.

BERNARD STEINMETZ.
